IGNITION CONTROL APPARATUS

Max Rall and Wilhelm Walther, Stuttgart, Germany, assignors to Robert Bosch Aktiengesellschaft, Stuttgart, Germany

Application June 25, 1930, Serial No. 463,759,
and in Germany June 29, 1929

10 Claims. (Cl. 200—5)

The present invention relates to ignition control apparatus and more particularly to a cut out switch and a switch for adjusting the time of ignition in internal combustion engines. Cut out switches, the movable switch portion of which is longitudinally displaceable and also rotatable in order to be able to cut out both ignition apparatuses simultaneously or separately during double ignition, are known. More particularly in connection with aircraft engines this results in the feature that ignition apparatus is employed in which completely advanced ignition and completely retarded ignition can be obtained and in which no gradual adjustment of the time of ignition is possible. For this purpose an ignition apparatus usually set at advanced ignition is for example placed at retarded ignition by switching on a second interruptor.

Such a switch is now, according to the present invention, combined with a press button switch for cutting out the ignition. The ignition control apparatus is preferably so arranged that when the ignition is cut out, the adjusting switch can only remain at retarded ignition.

One form of construction of the invention is illustrated by way of example in the accompanying drawings in which:—

Figure 1 is a longitudinal sectional view of the switch mechanism.

Figure 2 is a plan view of the combined ignition cut-out and adjusting switch mechanism.

Figure 3 is an interior view of the switch mechanism.

Figure 4 is an end view of the base plate with a diagram of the circuit connections.

Figure 5 is a sectional view of a switch part.

The switch mechanism is secured to a plate 1. Mounted on this plate are two handles, the upper of which is longitudinally movable as well as rotatable about its axis. The spindle or pin 3 of this switch can be pressed inwardly by a press button 2.

On the inner end of pin 3 is a smaller pin 4 on which is secured a switch roller 6, by means of a nut 5. The switch roller 6 consists of pressed insulating material in which is inserted a metal segment 7 as shown in Fig. 5. Two grooves 8 and 9 are formed on the circumference of the roller and serve simultaneously as guides and as stops for the ends of four contact springs 10. The pin 3 has a longitudinal slot 11 at its front end, through which a peg 13 passing through a hollow shaft 12, arranged over the pin 3, transmits the rotation of the hollow shaft 12 to the pin 3.

A bolt 15 is riveted in the plate 1 above the

press button switch and secures against rotation a plate 16 carried by the cut-out switch. The bolt 15 also acts as a stop for engagement with the stops 35 on the disc 34 to limit the rotation of the cut-out switch. A cam disc 17 provided with a cam projection 18 is carried by switch roller 6, but is prevented from rotating with the roller by bolt 15 which passes through an aperture in the disc 17. As the roller is moved in or out by pressing in or pulling out button 2, the disc 17 is moved with the roller and slides along the bolt 15.

The metal segment 7 on roller 6 extends completely around the roller at groove 9, but the extension 38 (see Fig. 5) located at groove 8 extends only partly around the roller. When the ends of contact springs 10 engage groove 9, all springs are connected together through the segment 7. When the springs engage groove 8, in one position of handle 14 the extension 38 connects the grounded spring with the spring connected to one ignition device, and in the other extreme position of the handle it connects the grounded spring with the spring corresponding to the other ignition device. In the center position of the handle 14, the grounded spring only is connected to extension 38.

The switch for adjusting the time of ignition is a rotating switch having two alternative positions. It consists of a bush 19, which is secured in the switch cover 1, a pin or spindle 20 on which is screwed a switch handle 21 and an oval contact disc 22 arranged to bridge two contact springs 23 in one position. A drum shaped spring casing 24 is firmly mounted on the switch spindle 20. A spiral spring 25 is mounted inside of casing 24 and the inner end of this spring is secured to a flap extension 26 formed on disc 16 and extending into the opened end of the drum 24. The outer end of the spring 25 is formed as a depressible lug 36 which projects through a slot 27 formed in the side of casing 24. The lug 36 is positioned to engage the cam 18 on the disc 17 when the cut-out switch is in running position, but when the cut-out switch is moved to the cut-out position the disc 17 moves out of engagement with the lug 36. The spiral spring 25 is tensioned so that it normally tends to rotate the adjusting lever 21 in anti-clockwise direction from "advanced" to "retarded" position. The switch mechanism is covered on the rear side by a drum shaped metal casing 28 having a bottom plate 29 of insulating material, which is secured to plate 1 by two bolts 30 and nuts 31. Terminal lugs 32 for the springs 10 and lugs 33 for the

springs 23 are arranged on the connecting plate 29.

The switch works as follows:—

When the engine is at rest, the button 2 of the cut-out switch is pressed down. In this position of the button the cam disc 17 is displaced so far inwardly that the cam 18 of the cam disc is no more in the way of the lug 36 of the spring 25 and, therefore, the ignition adjusting switch 21 is turned to retarded position by the force of spring 25. Thereby the disc 22 on the switch spindle 20 bridges over the two springs 23, which are connected to the terminals of the interrupter 37 for retarded ignition of the double interrupters 37 of two ignition devices M_1 and M_2 . Since contact disc 22 is grounded, the retarded interrupters 37 are grounded or connected in parallel with the advanced interrupters 37' when disc 22 bridges contact springs 23 and the advanced interrupters 37' are thereby made ineffective because then, of course, the primary circuit or circuits will not be interrupted until the retarded interrupters 37 open. Reference is made to the patent to Erich Klaiber 1,861,417 May 31, 1932 for a more detailed disclosure of a double interrupter of the type disclosed herein. Also, when button 2 is pushed in, both ignition devices, which are electrically connected to two diametrically opposed springs 10, are short circuited because all springs 10 are connected together by the metal segment 7, and one of the springs 10 is grounded.

Before starting the engine, the button 2 is drawn out. By this the short circuit of one or also of both ignition devices is eliminated according to the position of the rotating handle 14. By the handle 14 it is possible to examine the devices separately in operation. When handle 14 is set on " M_1 " the segment of part 38 connects the spring 10 of apparatus M_1 with the grounded spring 10, and only apparatus M_1 is short circuited. In the same manner apparatus M_2 is short circuited when handle 14 is set on " M_2 ". In the position " M_1-M_2 " of handle 14 the segment part 38 touches only the grounded spring 10 and, therefore, both devices are in operation.

When the engine is running, the adjusting lever 21 can be set in or turned to the position for advanced ignition, wherein the lug 36 of the spring 25 engages the cam 18 of the disc 17 which is also drawn out together with the button 2, spring lug 36 being depressed within casing 24 as it passes over the face of the cam to permit such turning. The adjusting lever is latched in this position by engagement of the lug 36 with the cam projection 18, but the lever may be moved by hand to the ignition retarding position by applying sufficient force to cause the lug 36 to ride over the cam projection 18, lug 36 being depressed within casing 24 so that it can clear lug 36 and thus permit turning of the casing and adjusting lever 21. If the adjusting lever is not returned to the retarding position by hand but the ignition is directly cut out by pressing the button 2, then the adjusting lever is not allowed to remain at advanced ignition. The lever is turned back by force of the spring 25 as the cam 18 is moved out of engagement with lug 36 upon pressing down the button 2.

What is claimed is:

1. Ignition control apparatus comprising an axially displaceable and rotatable cut out switch, contact elements associated with said cut out switch and adapted to be connected and disconnected by axial or rotary movement of said switch, an adjusting switch for varying the igni-

nition timing, and control means for the adjusting switch connected to the cut-out switch.

2. Ignition control apparatus comprising an axially displaceable and rotatable cut out switch, contact elements associated with said cut out switch and adapted to be connected and disconnected by axial or rotary movement of said switch, an adjusting switch for varying the ignition timing, contact elements associated with said adjusting switch and adapted for connection with at least two alternative interruptors and means carried by said switches for ensuring that the adjusting switch is in the position for retarded ignition when the cut out switch is in the cut out position.

3. Ignition control apparatus comprising an axially displaceable and rotatable cut out switch, contact elements associated with said cut out switch, an adjusting switch for varying the ignition timing, contact elements associated with said adjusting switch and adapted for connection with at least two alternative interruptors, resilient means tending to move the adjusting switch into the position for retarded ignition, and detent mechanism carried by said switches for holding the adjusting switch in the position for advanced ignition, said detent mechanism being adapted to be released when the cut out switch is moved into its cut out position.

4. Ignition control apparatus comprising an axially displaceable and rotatable cut out switch, contact elements associated with said cut out switch, a rotatable adjusting switch for varying the ignition timing, contact elements associated with said adjusting switch and adapted for connection with at least two alternative interruptors, resilient means tending to move said adjusting switch into the position for retarded ignition and a detent member for retaining the adjusting switch in the position for advanced ignition, said detent member being axially movable with the cut out switch so that it is disengaged from the adjusting switch when the cut out switch is moved into the cut out position.

5. Ignition control apparatus comprising an axially displaceable and rotatable cut out switch, contact elements associated with said cut out switch, a rotatable adjusting switch for varying the ignition timing, contact elements associated with said adjusting switch and adapted for connection with at least two alternative interruptors, a spiral spring on the spindle of the adjusting switch tending to move the adjusting switch into the position for retarded ignition, a projecting member angularly displaceable with the adjusting switch and an angularly fixed plate member having a cam edge adapted for engagement with said projecting member to hold the adjusting switch in the position for advanced ignition but adapted to move axially with the cut out switch on movement of the same into the cut out position to permit return of the adjusting switch into the position for retarded ignition.

6. Ignition control apparatus as claimed in claim 5 in which the projecting member is resiliently mounted and is adapted to yieldingly engage the cam edge of said plate member.

7. Switch means comprising a rotatable and axially displaceable switch member, contacts cooperating therewith, a second switch member rotatable to either of two positions, contacts cooperating therewith, resilient means for normally holding said second switch member in one of said two positions, and means carried by the first switch member cooperating with means carried

- by the second switch member to hold said second switch member in the other position thereof when said second switch member is moved to said other position.
5. Switch means comprising a rotatable and axially displaceable switch member, contacts co-operating therewith, a second switch member rotatable to either of two positions, contacts co-operating therewith, resilient means for normally holding said second switch member in one of said two positions, and means carried by and axially displaceable with said first switch member, and abutment means carried by and rotatable with said second switch member, said cam means movable by said first switch member into and out of the path of movement of said abutment means, said cam means engaging said abutment means when said cam means has been moved into the path of said abutment means and said second switch member has been moved to the other position to hold said second switch member in said other position, movement of said abutment means out of the path of said cam means releasing said engagement and permitting the second switch member to return to the first position.
10. Switch means comprising a rotatable and axially displaceable switch member, contacts co-operating therewith, a second switch member rotatable to either of two positions, contacts co-operating therewith, resilient means for normally holding said second switch member in one of said two positions, and means carried by and axially displaceable with said first switch member cooperating with means carried by and rotatable with said second switch member to hold
15. said second switch member in the other position thereof when said second switch member is moved to said other position, axial displacement of said first-mentioned means permitting said second switch member to return to the first position.
20. 9. Switch means comprising a rotatable and axially displaceable switch member, contacts co-operating therewith, a second switch member rotatable to either of two positions, contacts co-
- operating therewith, resilient means for normally holding said second switch member in one of said two positions, cam means carried by and axially displaceable with said first switch member, and abutment means carried by and rotatable with said second switch member, said cam means movable by said first switch member into and out of the path of movement of said abutment means, said cam means engaging said abutment means when said cam means has been moved into the path of said abutment means and said second switch member has been moved to the other position to hold said second switch member in said other position, movement of said abutment means out of the path of said cam means releasing said engagement and permitting the second switch member to return to the first position.
10. Switch means as in claim 9 in which the abutment means is resiliently mounted and is adapted to yieldingly engage the cam means.

operating therewith, resilient means for normally holding said second switch member in one of said two positions, cam means carried by and axially displaceable with said first switch member, and abutment means carried by and rotatable with said second switch member, said cam means movable by said first switch member into and out of the path of movement of said abutment means, said cam means engaging said abutment means when said cam means has been moved into the path of said abutment means and said second switch member has been moved to the other position to hold said second switch member in said other position, movement of said abutment means out of the path of said cam means releasing said engagement and permitting the second switch member to return to the first position.

80. 8. Switch means comprising a rotatable and axially displaceable switch member, contacts co-operating therewith, a second switch member rotatable to either of two positions, contacts co-operating therewith, resilient means for normally holding said second switch member in one of said two positions, and means carried by and axially displaceable with said first switch member, and abutment means carried by and rotatable with said second switch member, said cam means movable by said first switch member into and out of the path of movement of said abutment means, said cam means engaging said abutment means when said cam means has been moved into the path of said abutment means and said second switch member has been moved to the other position to hold said second switch member in said other position, movement of said abutment means out of the path of said cam means releasing said engagement and permitting the second switch member to return to the first position.

85. 10. Switch means as in claim 9 in which the abutment means is resiliently mounted and is adapted to yieldingly engage the cam means.

90. 11. Switch means as in claim 9 in which the abutment means is resiliently mounted and is adapted to yieldingly engage the cam means.

95. 12. Switch means as in claim 9 in which the abutment means is resiliently mounted and is adapted to yieldingly engage the cam means.

100. 13. Switch means as in claim 9 in which the abutment means is resiliently mounted and is adapted to yieldingly engage the cam means.

105. 14. Switch means as in claim 9 in which the abutment means is resiliently mounted and is adapted to yieldingly engage the cam means.

110. 15. Switch means as in claim 9 in which the abutment means is resiliently mounted and is adapted to yieldingly engage the cam means.

115. 16. Switch means as in claim 9 in which the abutment means is resiliently mounted and is adapted to yieldingly engage the cam means.

120. 17. Switch means as in claim 9 in which the abutment means is resiliently mounted and is adapted to yieldingly engage the cam means.

125. 18. Switch means as in claim 9 in which the abutment means is resiliently mounted and is adapted to yieldingly engage the cam means.

130. 19. Switch means as in claim 9 in which the abutment means is resiliently mounted and is adapted to yieldingly engage the cam means.

135. 20. Switch means as in claim 9 in which the abutment means is resiliently mounted and is adapted to yieldingly engage the cam means.

140. 21. Switch means as in claim 9 in which the abutment means is resiliently mounted and is adapted to yieldingly engage the cam means.

145. 22. Switch means as in claim 9 in which the abutment means is resiliently mounted and is adapted to yieldingly engage the cam means.

150. 23. Switch means as in claim 9 in which the abutment means is resiliently mounted and is adapted to yieldingly engage the cam means.
